UNITED STATES PATENT OFFICE.

CHARLES W. CUNDIFF, OF OWENSBORO, KENTUCKY, ASSIGNOR TO OWENSBORO DITCHER & GRADER COMPANY, OF OWENSBORO, KENTUCKY, A CORPORATION OF KENTUCKY.

DITCHING AND GRADING MACHINERY.

Application filed August 31, 1923. Serial No. 660,443.

To all whom it may concern:

Be it known that I, CHARLES W. CUNDIFF, a citizen of the United States, residing at Owensboro, in the county of Daviess and State of Kentucky, have invented certain new and useful Improvements in Ditching and Grading Machinery, of which the following is a specification.

This invention relates to ditching and grading machinery, and provides a new type of same comprising certain features of construction and particularly a cutting-blade formed so as to produce a flat bottom ditch which is often desired and necessary in certain classes of ditching.

Another advantage of the invention is that it is provided with a new and improved manner of hitching, thereby rendering more direct control of the machine relative to the draft thereof.

Aside from the above features mentioned, the machine possesses all of the general construction embodied in the V type ditching and grading machines, and in addition many new features as will be clearly explained in the description.

Another advantage of the invention is the fact, that, due to its particular form of construction, it is rendered almost indestructible and will withstand considerable use without material depreciation thereof. All parts being readily accessible, they may be easily replaced with new ones. Also the machine is very simple in construction and operation and may be produced at a minimum cost and sold proportionately.

In the accompanying drawings:

Fig. 1 is a side elevation of the machine complete;

Fig. 2 is a plan view of same;

Fig. 3 is a perspective view taken from the inner side showing the manner of connection of the blade to the landside.

Referring more particularly to the details of construction of the machine, in the drawings the numeral 1 indicates angle-iron members which are arranged in parallel order, forming the landside of the machine, the horizontal portions forming the foot-board. Said angle-irons are substantially connected at their rear ends to plate 2 by means of bolts 3 which are retained by nuts 4. It will be noted that the top edge 5 of the plate 2 is curved and forming a slight concavity thereon, which aids in guiding the

machine while in operation. The front ends of said angles are connected by plate 6 secured by means of rivets 7. In the center of the parallel angle-iron members is a spacing tube 8 retained in position by the bolt 9 and nut 10, holes for receiving said bolt being provided in both the upper and lower angle-irons 1.

One of the most important features of the machine is the manner of hitch comprising the following parts:

An outer strap 11 as shown, and similar inner strap 12, as shown in Fig. 3, has a shoulder 13 in order to offset the strap 12 to provide ample space for the upright bar 14 which is connected to the straps 11 and 12 by means of bolt 15 and nut 16. Plate 6, and straps 11 and 12 are secured together by rivets 17. Standard clevis 18 is used as shown and holes 19 in bar 14 are provided for same, any one of which may be used according to the manner of hitch desired. A chain 20 of the desired length is employed for connection to any form of power for propulsion, and having a hook 21 connected thereto.

A very important feature of the machine is the cutting blade or mold-board 22, and it will be noted that same is provided with the lower portion 23, thereby producing a flat bottom cut whereas with a pointed blade the V shaped ditch is produced instead thereof; also the rear lower edge 22' of the blade elevates the end of said blade whereby the dirt is rapidly and properly discharged to the side of the ditch. Blade 22 is connected to the land side in the following manner:—A U shaped member 24 is connected to said blade by rivets 25. The rear end of the strap 12 is formed into a tubular hinge 26, and a bolt 27 is passed through the hinge 26 and the ends of the U-shaped member 24, and is retained by nut 28. Draft beam 29 is employed as shown, the front end of which is formed as at 30 with a hole to accommodate the double clevis 31. Threaded thumbscrews 32 are used for both the single and double clevises which have threaded holes in one side of their forks to receive same. The opposite end of the beam 29 is formed as at 33, and supported by the brackets 34 which are secured to the blade 22 by rivets 35. Hand-rail 36 is provided and formed into a shoulder at 37, the lower end passing through a hole in the end 33 of beam 29 act-

ing to retain the beam in place. The opposite end of rail 36 has a shoulder 38 to form a stop upon the top portion of clip member 39 which is connected to the blade 22. Ex-
5 tension beam 41 is provided, preferably of wood, the front end 42 being reduced some-
what in size in order to pass through the
clip 39 and also having a hole to accommo-
date the end of rail 36. In this manner the
beam 41 and the end of said rail are re-
tained in position as shown in Fig. 1.

In order to support the rear end of blade 22, drag-shoe 43 is employed, and is sup-
ported by a stem 44 which is connected to
15 same in any approved manner. A U-shaped
member 45 is riveted to clip 39 (rivets not
shown), which member 45 is provided with
holes to receive the stem 44 as will be clear-
ly seen in Figs. 1 and 2, holes 46 in stem 44
20 being provided to receive pin 47 in order
that the elevation of the end of blade 22 may
be adjustable up or down.

A shoe 48 is used as shown and connected
25 to the blade 22 by bolts 49 which have coun-
tersunk heads, and retained by the nuts 50,
the purpose for same being to prevent the
point of the blade 22 from gouging the earth
or cutting too rapidly.

A U-piece 51 is secured to the blade by
30 rivets 52 where shown, and provided with
holes to receive bolt 53 which is held by nut
54. It will be clearly seen how the ends of
the brace bars 55 and 56 are connected there-
35 to, the opposite ends of said bars are con-
nected to the angle-irons 1 by means of a
bolt 57 passing through holes in the angle-
irons 1 and held in place by a nut 58. Holes
59 in angle-irons 1 permit the adjustment of
the blade to the landside.

40 A standard 60 with a hand-hole as shown,
is supported by clip 61 which is connected to
the blade 22 by rivets 62.

The right is herewith reserved to make

certain minor changes in the details of con-
struction, but without a departure from the
general principle disclosed, provided that it
becomes necessary to do so in the practical
field of the development of the machine for
the market. 45

I claim:

1. A machine of the character described
including a land-side, a mold-board having
a horizontal scraping edge, and an upward-
ly inclined rear edge, a clip secured to the
outer end of the mold-board, a drag-shoe, a
55 stem connected therewith, and means con-
nected with the stem for adjustably con-
necting it with the clip for raising or low-
ering the end of the mold-board.

2. A machine of the character described
60 including a land-side, a mold-board having a
horizontal scraping edge, and an upwardly
inclined rear edge, and a shoe secured to
the mold-board adjacent the horizontal
scraping edge for limiting the cutting depth
65 of the mold-board.

3. A machine of the character described
including a landside, a mold-board, a brack-
et secured thereto, draft means including
outer and inner straps secured together and
70 to the land-side, the inner strap having its
end terminating in a hinge for engaging
the bracket and pivotally connecting the
mold-board to the landside.

4. A machine of the character described
75 including a landside consisting of parallel
angle-irons spaced apart, a cutting-plate se-
cured to the angle-irons at the rear ends
thereof, draft means secured to the front
end of the land-side, a mold-board pivotally
80 connected to the land-side, and adjustable
brace-bars spaced apart and pivotally con-
nected to the mold-board and to the upper
and lower angle-irons.

In testimony whereof I affix my signature.

CHARLES W. CUNDIFF.
